Application April 6, 1939, Serial No. 266,354
In Great Britain April 28, 1938

4 Claims. (Cl. 235—61.6)

This invention relates to calculating machines and has for its object to provide means by which an amount obtained in such a machine can be rounded off to the next higher round value.

According to the present invention, a calculating machine comprises an amount register for an amount to be rounded off, a figure register for an adjustment figure, differencing means for obtaining automatically the difference between a lower portion of the amount in the amount register and the figure in the figure register, adding means for adding automatically the said difference to the said lower portion of the amount, and means operable under the control of the amount register to prevent operation of the adding means when said lower portion of the amount is zero. The said "lower portion of the amount" is that portion of the amount which requires adjustment in order to round off the amount, and the "adjustment figure" is the difference between two consecutive rounded-off amounts. Thus, if the amount is a period of time in hours and minutes and is to be rounded off to the next higher hour, the adjustment figure will be one hour, and the lower portion of the amount will be the minutes. The machine will obtain the difference between one hour and the minutes portion of the amount and will add this difference to the amount so as to round it off to the next higher hour. If the minutes portion of the amount is zero, the difference will be one hour and the addition of this difference to the amount will be suppressed, so that the rounded-off amount will be the original amount.

The arrangement set out in the preceding paragraph is applicable where the adjustment figure is a unit, such as an hour, in the notation of the amount, but is not applicable where the adjustment figure is a fraction, such as quarter of an hour, in the notation of the amount. In order that the machine may deal with the case when the adjustment figure is a fraction of a unit, the differencing means may be arranged also to obtain the differences between the said lower portion of the amount and the multiples of the figure from twice the figure to the lowest multiple which is equal to a unit in the notation of the amount, inclusive, and the adding means may be arranged to add the smallest said difference to the said lower portion of the amount. For this purpose the differencing means may comprise an accumulator, means operable to enter the said lower portion of the amount, and the figure, into the accumulator in such manner as to obtain the difference between them, means for thereafter

entering the figure repeatedly into the accumulator in such manner as to obtain, at each entry, the difference between the difference in the accumulator and the figure, and control means operable under the control of the accumulator to interrupt the entries of the figure when the difference in the accumulator is a complement or is a true number (as may be predetermined), and the adding means may be arranged to add the difference, remaining in said accumulator after the last entry of the figure, to the lower portion of the amount. The control means should be arranged to operate when the difference is the complement if the figure is subtracted from the lower portion of the amount and to operate when the difference is a true number if the lower portion of the amount is subtracted from the figure. The machine will be arranged to operate in one or other of these alternative manners as may be found most convenient in practice. In this manner the machine is caused to obtain first the difference between the lower portion of the amount and the figure, then the difference between the lower portion of the amount and twice the figure, and so on. The number of such successive differencing operations which the machine must be arranged to perform is equal to the number of times which the adjustment figure will go into the next higher unit of the notation of the amount.

An embodiment of the present invention will now be described, by way of example only, as applied to a record card controlled tabulating machine and with reference to the accompanying drawings in which:

Figs. 1 and 1a together form a circuit diagram of mechanism for adjusting a period of time to the next higher quarter hour.

Fig. 2 is a diagrammatic showing of an accumulator and cycling mechanism.

Figs. 3, 4 and 5 show three numerical examples of the operation of the mechanism shown in Figs. 1 and 1a.

Fig. 6 is an isometric view of "fugitive one" entering mechanism.

The invention will be described as applied to the tabulating machine known commercially as the Hollerith Rolling total machine. A machine of this kind is described in Patent #2,174,699, granted to H. H. Keen October 3, 1939, which corresponds to British patent specification No. 422,135, to which reference may be had for a detailed explanation of the arrangement and operation of the machine.

The machine is controlled by record cards

which may be arranged in groups. As each card passes conventional lower brushes, the amount on it can be read and entered into an accumulator in the machine. Normally four or six such accumulators are provided. The amount read from the card may also be printed by printing mechanism which is divided into printing banks. When the last card of a group has passed the lower brushes, conventional automatic group control mechanism comes into action in a known manner and initiates one or more total taking cycles.

The present machine is provided with a minor multi-contact relay. This relay is under the control of the automatic group control mechanism and, when a minor group change occurs, the minor multi-contact relay is energized.

The accumulators are conventional Hollerith accumulators and are controlled by accumulator magnets CT (Fig. 2) of which there is one for each denomination of the accumulator. As usual, each magnet, when energized, causes the entry of a digit into its denomination of its accumulator, and the value of the digit depends upon the time at which the magnet is energized. In Fig. 1 there are shown three magnets CT of accumulators 1, 2 and 3, which accumulators are designated accumulator 1, accumulator 2 and accumulator 3. Each of these accumulators is arranged to sum hours and minutes and is provided with two denominations for registering the minutes and a number of higher denominations of which only one is shown for registering the hours. Each denomination comprises an accumulator wheel, and the units of minutes and hours wheels are arranged to complete a revolution in ten steps so as to add from 0 to 9 and then turn to 0. The tens of minutes wheel is arranged to complete a revolution in six steps so as to add from 0 to 5 and then turn back to 0. In the drawings the highest magnet CT in each group controls the units of hours denominations, the next lower magnet controls the tens of minutes and the lowest controls the units of minutes denomination.

Each accumulator is provided with a conventional reading-out mechanism. As these mechanisms are identical, only that for accumulator 1 will be described. This mechanism comprises a brush 10 (see Fig. 2) for each denomination which moves in step with the accumulator wheels to connect a common strip 11 to one of ten segments 12. In the case of the tens of minutes denomination there are only six segments 12a (see Fig. 1). Each segment 12 or 12a corresponds to a different digit and the arrangement is such that each brush 10 connects the segment 12 or 12a corresponding to the digit registered in its denomination to the related common strip 11. All the segments 12 corresponding to the same digit in one accumulator are connected together and to the center blade of relay contacts 1D4a. The circuits continue through the normally closed contacts 1D4a and wires 13 to an emitter E10. This emitter E10 as well as emitter E6 (Fig. 1) are located in the machine and driven in the same manner as emitters E1 and E2 of Patent #2,174,699 (see Fig. 4 thereof). This emitter rotates in synchronism with the operation of the accumulators and the printing mechanism so as to connect each row of segments 12 corresponding to a particular digit in circuit at the time in the cycle appropriate to that digit. If a brush 10 engages a segment 12 for a particular digit, the circuit will be continued through this brush and the segment 11, so as to transmit an electrical

impulse timed to represent the digit registered in the accumulator. This impulse can be employed to control an accumulator magnet in the same or another accumulator to cause the addition of the digit or to control the printing mechanism to print that digit.

If the contacts 1D4a are shifted, the connections will be changed in a complementary manner, so that the impulse transmitted will represent the nines complementary digit to the digit registered in the accumulator. Thus, it is possible to read out of the accumulator either the amount registered in that accumulator or the nines complement of the amount registered in that accumulator. The segments 12a are connected in a similar manner through contacts 1D5a. That is, the segments 12a are connected through normally closed relay contacts 1D5a to correspondingly numbered segments of an emitter E6. If the contacts 1D5a are shifted, the connections will be changed in a complementary manner, so that the number read out is the fives complement of the number standing on segments 12a. This order being the tens of minutes order does not record higher than 5 and transfers when it passes from 5 to 0.

Each accumulator has six multi-contact relays associated with it. These relays will be referred to as distributors, and the contacts 1D4a and 1D5a of the distributors 1D4 and 1D5 have already been referred to. Distributors 1D0, 1D2, 1D3, 1D4 and 1D5 are associated with accumulator 1; distributors 2D0, 2D2, 2D3, 2D4 and 2D5 are associated with accumulator 2, and distributors 3D0, 3D2, 3D3, 3D4 and 3D5 are associated with accumulator 3. The functions of these distributors are as follows: As previously explained, the distributors 1D4 and 1D5 cause, when energized, the nines complement of the amount in accumulator 1 to be read out. The distributors 2D4 and 2D5 serve the same function for accumulator 2, and the distributors 3D4 and 3D5 perform the same function for accumulator 3. The distributors 1D0, 2D0 and 3D0 serve, when energized, each to connect sockets TS (Fig. 1) associated with its accumulator to the reading-out mechanism of that accumulator. From the sockets TS of the particular accumulator, plug connections can be made to sockets R of another accumulator. The distributors 1D2, 2D2 and 3D2, when energized, serve each to connect the sockets R of the associated accumulator to the magnet CT of that accumulator through the normally closed contacts 1D3a, 2D3a or 3D3a. Thus, in Fig. 1, the sockets TS of accumulator 3 are connected to the sockets R of accumulator 2. If the distributors 3D0 and 2D2 are energized, a circuit can be completed through the reading-out mechanism of accumulator 3, the normally open contacts 3D0a, the sockets TS of accumulator 3, plug connections 20, the sockets R of accumulator 2, the contacts 2D3a and 2D2a and the accumulator magnet CT of accumulator 2. In this manner the amount standing in accumulator 3 is transferred to accumulator 2 and added to the amount initially registered in accumulator 2. If the distributors 3D4 and 3D5 had been energized, the nines complement of the amount in accumulator 3 would have been transferred to accumulator 2 and added to the amount in accumulator 2. This is equivalent to subtracting the amount in accumulator 3 from the amount in accumulator 2, so that accumulator 2 will be left registering the difference between these amounts.

From the foregoing it will be seen that, if an

accumulator is to receive an amount from another accumulator, its distributor 1D2, 2D2 or 3D2 is energized. If an accumulator is to transmit an amount additively to another accumulator, its distributor 1D0, 2D0 or 3D0 is energized. If an accumulator is to transmit an amount subtractively to another accumulator, its distributors 1D0, 1D4 and 1D5 or 2D0, 2D4 and 2D5 or 3D0, 3D4 and 3D5 are energized.

When it is desired to reset an accumulator, its distributors 1D2, 1D3, 1D4 and 1D5 or 2D2, 2D3, 2D4 and 2D5 or 3D2, 3D3, 3D4 and 3D5 are energized. This has the effect of connecting the accumulator magnets of the accumulator to the reading-out mechanism of that accumulator and also adjusting the reading-out circuits, so that the impulses transmitted represent the complement of the amount in the accumulator. In other words, the accumulator subtracts the amount it contains.

The subtraction is performed by adding the nines complement, and it is therefore necessary to enter the so-called "fugitive unit," as is well known. Normally, this is effected by arranging for the highest denomination of the accumulator to transfer to the lowest denomination of the accumulator so that, when the accumulator wheel for the highest denomination turns from 9 to zero, one unit is added to the lowest denomination by a tens carry operation. This will leave the accumulator registering either the true amount if it is positive or the nines complement of the true amount if that amount is negative. If an accumulator is reset, the addition of the complement will leave it registering the nines complement of zero and no transfer will take place from the highest wheel. Special provision is made for entering the fugitive unit under these conditions, in order that the accumulator may be reset to zero.

The "fugitive one" entering mechanism is shown in Fig. 6 in which 2 represents the well known carry lever latches in the highest and lowest orders of an accumulator. When the highest order wheel passes from 9 to 0, its latch 2 is depressed and through a pair of pivoted and articulated levers 3 and 4 causes depression of the lowest order latch 2 by acting on a plate 4' secured thereto. Depressing of latch 2 in the lowest order will cause a "1" to be entered, as is well known. Disposed beneath plate 4 is a magnet designated 2FU which, if energized, will depress lever 2 for the same purpose of entering an elusive one. The magnet is used to enter a one during resetting operations will be explained.

The printing mechanism is of the kind normally employed in Hollerith tabulating machines and is controlled by printing magnets PR. As is usual, the time in the cycle at which each magnet PR is energized determines the digit which will be printed under the control of that magnet. In Fig. 1 two banks of printing magnets PR are shown, and these banks will be referred to as bank 2 and bank 3. Distributor 2D1 is associated with printing bank 2 and the distributor 3D1 is associated with printing bank 3. The distributor 2D1 must be energized when it is desired to print a total by means of printing bank 2, and the distributor 3D1 must be energized when it is desired to print a total by means of the printing bank 3.

In addition to the distributors, the machine is provided with three distributing relays DR3, DR4 and DR5 which are not associated with any ac-

cumulator. The normally open contacts DR3a of the relay DR3 are inserted in the plug connections 21 between the sockets TS of accumulator 2 and the sockets R of accumulator 3, so that the amount in accumulator 2 can be transferred to accumulator 3 if the distributing relay DR3 is energized. The normally closed contacts DR5a of the distributing relay DR5 are connected in the plug connections 22 between the sockets TS of accumulator 1 and the sockets R of accumulator 2, so that the transfer can be made from accumulator 1 to accumulator 2, provided the distributing relay DR5 is deenergized. It should be mentioned that the plug connections 22 are made for each denomination of accumulators 1 and 2, whereas the plug connections 20 and 21 are made only for the two lower denominations, that is, the tens and units of minutes denominations, of accumulators 2 and 3. The center blades of the contacts DR4a are connected by plug connections 23 to sockets 24 associated with accumulator 3. The normally closed contacts DR4a are plug connected by connections 25 to the normally open contacts 2D1a while the normally open contacts DR4a are plug connected to the normally open contacts 3D1a. The plug connections 23 connect the contacts DR4a to the reading-out mechanism of accumulator 3. If the distributing relay DR4 is deenergized and the distributor 2D1 is energized, the magnets PR of the printing bank 2 are connected to the reading-out mechanism of accumulator 3, so that the amount in accumulator 3 can be printed. If the distributing relay DR4 and the distributor 3D1 are both energized, the magnets PR of the printing bank 3 will be connected to the reading-out mechanism of accumulator 3, and the amount registered in accumulator 3 can be printed by the printing bank 3. The distributing relay DR4 thus determines whether the amount in accumulator 3 shall be printed by the printing bank 2 or by the printing bank 3.

The arrangement of the accumulators, reading-out mechanism and distributors is substantially the same as that described in the prior specification aforesaid, and reference may therefore be made to this specification for more detailed explanation of the operation of its parts. The manner in which the various distributors and distributing relays are energized selectively will now be described.

It has previously been mentioned that the machine is provided with minor multi-contact relays. The contacts of the minor relay are shown in Fig. 1a and are designated Mi. If a minor group change occurs, all the contacts Mi will close. The coil of the distributor 1D0 will then be connected through the now closed contact Mi to a socket 21. For the purposes of the present invention, no plug connection is required to socket 21 as magnet 1D0 is not utilized.

It may be explained that, in order to simplify the disclosure, the several contacts Mi are illustrated as being connected together for common operation by a manual key 75. It will also be assumed that initial entries into the accumulators are manually made as by turning the indicating wheels forwardly but it will be understood that such initial entries may be made under record card control in the well known manner. In other words, the invention as herein disclosed is devoid of all automatic control features. Three accumulators and a printing mechanism are utilized and are driven in unison from a common source of power so that they are in con-

tinuous operation. The accumulators each receive an initial entry by manual adjustment of their indicating wheels and after switch T2 (Fig. 1) is closed and the Mi contacts are shifted, the clutch releasing finger 88 (Fig. 2) is operated.

Referring now to Fig. 2, 76 represents the accumulator drive shaft which may be in constant rotation, each rotation being designated a cycle of operation. Shaft 76 corresponds to the shaft 513 of Patent #2,174,699, shown in Fig. 4 thereof, and this shaft 513 rotates as long as the main clutch of the machine remains engaged. As explained in the patent, shaft 513 rotates during the whole time that the machine is in operation. Fig. 4 of the patent also shows the location on the corresponding shaft 513 of gears 514 which correspond to gears 78 of Fig. 2. When any magnet CT is energized, it causes tripping of the clutch 77 to drive gear 78 which in turn drives the indicating wheel 79 and gear 80 which carries the brush structure 10. As explained, the units of minutes and hour denominational wheels 79 are arranged to advance in increments of one-tenth of a revolution for each unit entered, while the tens of minutes wheel 79a is arranged to advance in increments of one-sixth of a revolution for each unit entered therein.

After an initial entry has been made in each of the three accumulators in accordance with a particular problem, as will be explained, the machine is to enter upon a succession of calculating cycles during which transfer operations will take place according to the plugging arrangement. In the complete machine such cycles are automatically initiated upon a group change but for the purposes of the present disclosure there is shown a diagrammatic arrangement whereby the cycles may be manually initiated. A gear 81 secured to shaft 76 drives a gear 82 with a ratio of 10:1 so that during one complete rotation of gear 82, shaft 76 makes ten revolutions. Integral with gear 82 is a clutch disk 83 having a notch 84. The gear 82 is free on a shaft 85 to which is secured an arm 86 whose free end supports a spring-pressed clutch dog 87 normally held in the position shown.

Operation of a key 88 will rock lever 89 to release dog 87 for engagement with disk 83 whereupon the arm 86 and shaft 85 will rotate with gear 82. Also secured to shaft 85 and insulated therefrom is a brush structure 90, one of whose brushes cooperates with a collector ring 91 and the other with ten segments 92, so that during each of the ten cycles now following the brush 90 will connect a different segment 92 with the ring 91. After the shaft 85 has made a complete revolution, the dog 87 will engage lever 89 to effect declutching of the parts.

In Fig. 1a the parts 90, 91 and 92 are represented diagrammatically to indicate that brush 90 successively traverses the segments 92 in the order 10, 9, 8, etc. Each segment 92 is wired to a relay magnet generally designated C so that throughout each of the ten cycles one of the magnets C10, C9, etc., is energized to close its related contacts C10a, C9a, etc., each of which contacts has a blade thereof connected to a plug socket 93.

If it is desired to energize the distributor 1D0 in a particular cycle, the socket 27 will be plug connected to socket 93 of the pair of contacts of the C relay which is energized in that cycle. The distributor 1D0 will then be energized in that cycle. For the purposes of the operations to be described later, it is not necessary to energize the

distributor 1D0, so that no plug connections have been made to the socket 27.

The circuit arrangement for the distributor 1D0 is repeated for the distributor 1D2 and also for a relay 1S and a relay 1R. The distributor 1D0 can thus be energized in any total taking cycle, as these ten special cycles will hereinafter be called, to cause accumulator 1 to transmit an amount additively to another accumulator. In 10 the same way the distributor 1D2 can be energized to cause accumulator 1 to accept an amount from another accumulator. The relay 1S can be energized in order to cause accumulator 1 to transmit an amount subtractively to another accumulator. When energized, this relay closes its contacts 1Sa to energize the distributor 1D0 and its contacts 1Sb to energize the distributors 1D4 and 1D5. As previously mentioned, the energization of the distributors 1D0, 1D4 and 15 1D5 conditions accumulator 1 to transmit an amount subtractively. The relay 1S is provided in order to simplify the plugging of the machine and make it possible to condition accumulator 1 to transmit an amount subtractively under specified conditions with the insertion of a single plug connection only. The relay 1R controls the re-setting of accumulator 1 and, when energized, closes its contacts 1Ra, 1Rb and 1Rc to energize the distributors 1D2, 1D3, 1D4 and 1D5. The relay 1R is also used to simplify the plugging of 20 the machine.

It will be noticed that the distributor 1S is connected to contacts C1a by a plug connection 32 to the plug socket 33, so that the relay 1S will be energized in cycle 1 on a group change. Plug connections 34 connect the socket 33 to contacts C6a, C5a, C4a, so that the relay 1S will also be energized in cycles 6, 5 and 4 on group change. This plugging ensures that accumulator 1 will be 25 30 conditioned to transmit an amount subtractively in cycles 6, 5, 4 and 1 when a minor group change occurs.

The circuits for the distributors associated with accumulators 2 and 3 are the same as those of the distributors associated with accumulator 1, and accumulators 2 and 3 also have associated relays 2S, 2R and 3S, 3R corresponding to the relays 1S and 1R. The manner in which the plug connections are made in respect of accumulators 2 and 3 will be apparent from the description of the 35 40 operation of the machine which will follow.

The distributors 2D1 and 3D1, which are associated with the two printing banks, are also connected to contacts Mi in the manner described above with reference to the distributor 1D0, so that these distributors can be energized in any 45 50 cycle on a group change.

It will be assumed that the machine is employed for the purpose of calculating the total number of hours worked by employees in a week, 55 and that the weekly total is to be rounded off to the next higher quarter of an hour. The period of fifteen minutes will be referred to as the adjustment figure and accumulator 1 is employed as a register for this figure. The total hours worked will be accumulated in accumulator 3 which will be referred to as the amount accumulator, while accumulator 2 is employed to obtain the amount which is to be added to the actual time worked, in order to obtain the rounded-off time. Accumulator 2 will be referred to as the difference 60 65 70 75 accumulator.

Accumulator 1 will first be adjusted to contain therein the adjustment figure which, for example, may be 15 representing fifteen minutes. Ac-

cumulator 2 will be adjusted to represent the nines complement of this adjustment figure which for fifteen minutes will be 99944, and accumulator 3 will be adjusted to register an amount representing total time worked, for example, 48 hours and 54 minutes. It will be appreciated, of course, that these entries may be made under control of perforated records from one of which the entry of the adjustment figure and its complement may be made, while the time worked may represent a total obtained from a group of cards.

The minor control key 75 (Fig. 1a) is now operated to close and hold closed the M_i contacts and the machine is ready to begin the operation of rounding off the total time in accumulator 3. These operations are initiated by operation of key 88 which releases the brush 90 for a revolution or ten accumulator cycles. For the present problem, cycles 10, 9 and 8 are idle cycles as no plug connections are made to their sockets 93.

The amounts standing in the accumulators are indicated along the first line of Fig. 3.

During cycle 7, a circuit will be established from left side of line 102 (Fig. 1a), collector ring 91, brush 90, segment 92 (7), relay magnet C7 to line 100. A circuit will then be established through contacts C1a, plug connection 40, socket 101, contacts M_i , the distributor 2D2 to left side of line 102, so that the accumulator 2 will be conditioned to accept an amount. A second circuit will be established through contacts C7b, a plug connection 41, socket 103, contacts M_i and the distributor 3D0, so that accumulator 3 will be conditioned to transmit an amount additively. The amount will be transmitted over the plug connections 20 (Fig. 1) to accumulator 2 and will consist of the minutes digits registered in accumulator 3. This is shown in Fig. 3 in the row labeled cycle 7, and it will be seen that the minutes 54 is entered into accumulator 2 and added to the complement 99944 already in that accumulator. This is equivalent to subtracting 15 minutes from the actual minutes in the time worked and leaves accumulator 2 registering 39 minutes. It will be noted that the addition of 54 to 99944 resulted in the transfer from the highest wheel of the accumulator, and this transfer is made to the lowest wheel. In Fig. 3 the transferred unit is shown to the left of the total and has been added in. The transfer circuits are traceable in Fig. 1 as follows: from line 100, emitter E10, wires 13 of accumulator 3, normally closed contacts 3D4a, segments 12, brushes 10 to strips 11 of the first and third orders. A parallel circuit extends from line 100, emitter E6, contacts 3D5a to segments 12a, brush 10 to strip 11 of the second or tens of minutes order. From here the circuits extend to lower (now closed) contacts 3D0a, sockets TS, plug connections 20 (in the two lowest orders only), sockets R of accumulator 2, upper contacts 2D3a, upper contacts 2D2a (now closed), magnets CT to line 102.

The cycle relay C7 also closes its contacts C7c to complete a circuit including a plug connection 42 (Fig. 1a) through the distributor 2D1 traceable from contacts C7c, connector 42, socket 104, contacts M_i , magnet 2D1 to line 102. The distributing relay DR4 is not energized in this cycle, so that its contacts DR4a are as shown in Fig. 1. With the contacts 2D1 shifted, the magnets PR of printing bank 2 are connected to the reading-out mechanism of accumulator 3, so that the actual time worked will be printed by printing bank 2 under the control of accumulator 3. This is indicated in Fig. 3 by the figures 48 54

under the heading "Bank 2" and opposite the cycle 7. The printing circuits are traceable from the common strips 11 of accumulator 3 to sockets 24, connections 23, upper contacts DR4a, upper contacts 2D1a (now closed), print magnets PR of banks 2 to line 102.

Thus, at the end of cycle 7, the machine has subtracted, in accumulator 2, 15 from 54 and obtained a positive difference of 39. The machine will now proceed to subtract 15 from the amount in accumulator 2 repeatedly until a negative difference is obtained. This negative difference is the amount which, when added to the actual time in accumulator 3, will round it off to the next higher hour. In effect, the machine subtracts 15, 30, 45 and 60 from the minutes in the actual time worked and adds the smallest negative difference to the actual time worked. It will be appreciated that this is equivalent to subtracting the minutes in the actual time worked from 15, 30, 45 and 60 and adding the smallest positive difference to the actual time worked. In either case, the difference between the actual time worked and twice the adjustment figure, three times the adjustment figure and four times the adjustment figure are calculated, and it is a matter of convenience whether the actual time should be subtracted or whether the adjustment figure and its multiples should be subtracted. The latter procedure is preferable, as it involves the least departure from standard practice in the machine.

Referring now to Fig. 3, it will be seen that in cycles 6, 5 and 4, the complement of the adjustment figure in accumulator 4 is transferred to accumulator 2. This is equivalent to subtracting 15 from the difference remaining in accumulator 2. The machine will then be left with a difference of 24 minutes at the end of cycle 6, 9 minutes at the end of cycle 5 and minus 6 minutes at the end of cycle 4. This last difference appears in the form of the complement 99953. These operations require the energization of the relay 1S to condition accumulator 4 to transmit subtractively and of the relay 2D2 to condition accumulator 2 to accept the amount transmitted. The relay 1S is energized in cycles 6, 5 and 4, owing to the closure of the contacts C6a, C5a and C4a (Fig. 1a), while the relay 2D2 is energized owing to the closure of the contacts C6b, C5b and C4b, the circuits including plug connections similar to 40.

During cycle 3 the complement of the minutes digits registered in accumulator 2 is transferred to accumulator 3. The amount 53 in accumulator 2 is the complement of 6 and the complement of 53 is 6, so that 6 minutes will be entered into the accumulator 3 and added to the actual time in accumulator 3 to give a rounded-off time of 49 hours. This transfer requires the energization of the relay 2S which is effected by the closure of contacts 3Ca over a circuit including a plug connection 43. The distributor 3D2 is also energized on the closure of contacts 3Cb, so that accumulator 3 will accept the amount transferred from accumulator 2. A plug wire 44 provides for the energization of the distributor 3D2 in cycle 3. It will be noted that energization of relay 2S closes its contacts 2Sa to energize magnet 2D0 and closes its contacts 2Sb to energize magnets 2D4 and 2D5.

During cycle 3 relay magnet DR3 is also energized to shift its contacts DR3a (Fig. 1) so that transfer circuits can be completed from strips 11 of accumulator 2, lower contacts 2D0a (now

closed), upper plug connections 21, right hand contacts DR3a, lower plug connections 21, upper contacts 3D3a, upper contacts 3D2a (now closed) to magnets CT of accumulator 3. The manner in which magnet DR3 is energized will be more fully explained hereinafter.

In cycle 2 the amount in accumulator 3 is printed by the printing bank 3. For this purpose the distributor 3D1 is energized on the closure of contacts C2c to which its coil is connected by a plug wire 45. A plug connection 46 connects the distributing relay DR4 to contacts C2b, so that both the distributor 3D1 and the distributing relay DR4 are energized in cycle 2. This, as previously explained, allows of the amount in accumulator 3 being printed by the printing bank 3. The relay 2R is connected by a plug wire 47 to contacts C2d, so that this relay will be energized in cycle 2 and will condition accumulator 2 to be reset during cycle 2. These operations are shown opposite cycle 2 in Fig. 3.

Relay 2R closes its contacts 2Ra and 2Rb to cause energization of relay magnets 2D2 and 2D3 respectively and also closes its contacts 2Rc to energize magnets 2D4 and 2D5 in series. Circuits through the contacts of these relays will cause the nines complement of the amount in accumulator 2 to be added thereto, but this would not involve the entry of the fugitive one from the highest to the lowest order as in such case there is no passage of the highest order wheel through zero. In order to reset the accumulator correctly to zero, the fugitive unit is added by the magnet 2FU (Fig. 1a) which, when energized, trips the tens carry mechanism of the lowest order so that this mechanism will operate in the normal manner to enter one unit to the lowest order. This magnet has a plug connection 105 to contacts C2a so that it is energized in cycle 2 at a time determined by closure of cam contacts 106 which close once each cycle at the appropriate time. The cam controlled contacts 106 are carried by the same shaft that carries the brushes of emitters E6 and E10.

In the last cycle, cycle 1, the contacts C1b close to energize the relay 3R whose contacts energize relays 3D2, 3D3, 3D4 and 3D5 so that the accumulator 3 will be reset. Contacts C1a and C1d also close to energize the relay 1S, and the distributor 2D2. This conditions accumulator 1 to transmit the nines complement of the adjustment figure and accumulator 2 to accept that complement. Thus, the nines complement of the adjustment figure is again set up in accumulator 2. Also during this last cycle contacts C1c through a plug connection cause energization of magnet 3FU to enter the fugitive one in accumulator 3 to zeroize the same, so that at the completion of the ten cycles accumulator 1 will contain the adjustment figure 15, accumulator 2 will contain the complement of 15, namely, 99944, and accumulator 3 will be clear. A new entry of an amount may now be again made in accumulator 3 and this amount printed in bank 2 and the rounded-off amount in bank 3.

The sequence of operations just described occurs when the minutes part of the time registered in accumulator 3 is from 46 to 59 minutes, inclusive. If this portion of the time is from 31 to 44 minutes, inclusive, a negative difference will be obtained at the end of cycle 5 and subtraction will be suppressed in cycle 4. If the minutes part of the original time is from 16 to 29 inclusive, the negative difference will be obtained at the end of cycle 6 and cycles 5 and 4

would be idle cycles, while if the minutes portion of the original amount is from 1 to 14 inclusive, the negative difference is obtained at the end of cycle 7 and cycles 6, 5 and 4 are idle cycles. In each case the subtraction of the adjustment figure is suppressed as soon as a negative difference is obtained, since the presence of a negative difference indicates that the correct amount has been obtained for addition to the original time.

Fig. 4 shows the sequence of operations which would occur if the original time had been 48 hours 15 minutes. Cycle 7 takes place as previously described, but the addition of fifteen to the complement of the adjustment figure is not sufficient to convert that complement into a true number, so that accumulator 2 still contains a complement at the end of cycle 7. Accumulator 2 is provided with a pair of contacts 50 (Figs. 1a and 2) which are controlled by the highest order wheel in the accumulator and close if that wheel registers 9 but open if the wheel registers any other figure. Thus, with the example shown in Fig. 4, the contacts 50 will be closed at the end of cycle 7 and at the beginning of cycle 6. Thus, during cycles 6, 5 and 4, circuits are completed through the contacts C6c, C5c and C4c, plug connections 51, a relay coil 52, the contacts 50 of accumulator 2 and the distributors 2D4 and 2D5. The energization of the two distributors has no effect upon the operation of the machine at this time. The coil 52 closes its contacts 52a (top Fig. 1a) so that circuits can be completed in each of cycles 6, 5 and 4 through contacts C6d, C5d and C4d, plug connections 107, the contacts 52a and the distributing relay DR5. This distributing relay opens its contacts DR5a which are included in the plug connections 22 by which the impulses representing the complement of the adjustment figure are transferred from accumulator 1 to accumulator 2. Since these contacts DR5a are open, the transfer of the complement of the adjustment figure to accumulator 2 will be suppressed in cycles 6, 5 and 4. Thus, the amount registered in accumulator 2 will remain unchanged from the end of cycle 7 to the beginning of cycle 3. This amount is the complement of zero, so that zero will be entered in accumulator 3. In other words, the original time will not be altered and will be printed as the rounded-off time. It will be appreciated that if the minutes portion of the original time had been more than fifteen but less than thirty-one, the adjustment figure in accumulator 1 would have been transferred subtractively to accumulator 2 in cycle 6, since the difference in accumulator 2 would only have become a complement at the end of cycle 6. Under these conditions cycles 5 and 4 would be idle cycles. In the same way cycle 4 alone is an idle cycle if the minutes portion of the original time is more than 30 and less than 46, while none of the cycles 6, 5 and 4 is idle if the minutes portion of the original time is more than 45.

If the minutes portion of the amount is 15, 30 or 45, the amount added to it will be zero, since the complement which will be obtained in accumulator 2 will be the complement of zero under these conditions. If, however, the original time is an exact hour, as is the case in the example shown in Fig. 5, the complement obtained in accumulator 2 will be the complement of 15 and will be obtained at the end of cycle 7. If no special provision were made, the 15 would be added in cycle 3 to the original time in accumulator 3 to give the rounded-off time of 48 hours and 15

minutes. In order to prevent this incorrect result, provision is made for suppressing the transfer from accumulator 2 to accumulator 3 in cycle 4 when both the minutes digits of the original amount are zero. For this purpose, relay coils TPD1 and TPD2 (Fig. 1) are connected by plug connections 53 in parallel with the printing magnets PR which print the minutes portion of the original amount. The emitters E6 and E10 are arranged in the usual manner to transmit impulses representing the significant digits only and do not transmit an impulse at the zero time in the cycle. If a printing magnet PR is not energized, the section of the printing mechanisms it controls is automatically positioned to print zero in the usual way. Thus, if a significant digit is to be printed by the tens of minutes printing magnet PR in bank 2, a circuit will be completed through this magnet and will branch through the magnet TPD1. If, however, the tens of minutes digit is zero, no circuit will be completed to the related magnet PR or to the relay coil TPD1. The magnet TPD2 will be energized in a similar manner if the units minute digit is significant, but not if it is zero. The relays TPD1 and TPD2, when energized, close their holding contacts TPD1b and TPD2b respectively to provide holding circuits through a switch T2 which is closed during the total taking cycles. This switch T2 may conveniently be closed by key 75 along with the Mi contacts or separately closed prior to a total taking operation. Thus, if the minutes portion of the original amount is zero, neither coil TPD1 or TPD2 will be energized, but in any other case, one or both of these coils will be energized.

These coils are energized during cycle 7 and later in cycle 3 contacts C3c (Fig. 1a) close so as to complete a circuit through connections 108, contacts TPD1a or TPD2a to the distributing relay DR3. This circuit is only completed if one or both of the relays TPD1 and TPD2 is energized. The distributing relay DR3 is energized in cycle 3 if the minutes portion of the original time is not zero but is not energized if the minutes portion of the original time is zero.

The distributing relay DR3 closes its contacts DR3a (Fig. 1) when it is energized, so as to complete the connections by which the difference in accumulator 2 is transferred to accumulator 3. With the example shown in Fig. 5, the minutes portion of the original time is zero, so that the contacts DR3a will not be closed in cycle 3 and the transfer from accumulator 2 to accumulator 3 will be suppressed.

Cycles 7, 6, 5 and 4 may be described as differencing cycles, and the number of such differencing cycles is equal to the number of times which the adjustment figure goes into the next higher unit in the notation of the amount to be rounded off. Four cycles are necessary in the examples just given, since 15 minutes is a quarter of an hour. If the adjustment figure had been 20 minutes, only three differencing cycles would be needed. The total number of cycles could thus be reduced to six by plug connecting the contacts of the relay C6 in the manner shown for the relay C7 and omitting the plug connections for the relay C1. In a similar manner, it would be necessary to introduce two further cycles if the adjustment figure were 10 minutes.

While there has been shown and described and pointed out the fundamental novel features of the invention as applied to a single modification, it will be understood that various omissions and substitutions and changes in the form and de-

tails of the device illustrated and in its operation may be made by those skilled in the art without departing from the spirit of the invention. It is the intention therefore to be limited only as indicated by the scope of the following claims.

What is claimed is:

1. In a machine for rounding off an amount expressed in hours and minutes to the next higher quarter hour, a device settable to represent 15 minutes, an accumulator settable to represent the complement of 15 minutes, a second accumulator settable to represent the amount to be rounded off, said accumulators being adapted to accumulate hours and minutes as such, means for transferring the minutes part of the amount in the second accumulator to the first accumulator, means for transferring the amount in said device to the first accumulator in the form of a complement, cycling means for causing in turn an operation of said first named transferring means and three successive operations of said second transferring means, means operative under control of said first accumulator and said cycling means during each successive transferring operation for ascertaining whether the amount in the first accumulator is a complement, means controlled thereby when the amount is a complement for rendering subsequent operation of said second transferring means ineffective, means for transferring the true value of the amount standing in the first accumulator to the second accumulator whereby there will be added thereto a number of minutes to raise the amount in the second accumulator to the next higher quarter hour, said cycling means causing an operation of said last named means after said successive operations have taken place.
2. In a machine for rounding off an amount expressed in hours and minutes to the next higher predetermined even subdivision of an hour, a device settable to represent the minutes in said even subdivision, an accumulator settable to represent the complement of said minutes, a second accumulator settable to represent the amount to be rounded off, said accumulators being adapted to accumulate hours and minutes as such, means for transferring the minutes part of the amount in the second accumulator to the first accumulator, means for transferring the amount in said device to the first accumulator in the form of a complement, cycling means for causing in turn an operation of said first named transferring means and a plurality of successive operations of said second transferring means, means operative under control of said first accumulator and said cycling means during each successive transferring operation for ascertaining whether the amount in the first accumulator is a complement, means controlled thereby when the amount is a complement for rendering subsequent operation of said second transferring means ineffective, means for transferring the true value of the amount standing in the first accumulator to the second accumulator whereby there will be added thereto a number of minutes to raise the amount in the second accumulator to the next higher subdivision, said cycling means causing an operation of said last named means after said successive operations have taken place.
3. In a machine for rounding off an amount expressed in hours and minutes to the next higher quarter hour, a device settable to represent 15 minutes, a first accumulator settable to represent

15 minutes as a negative amount, a second accumulator settable to represent the amount to be rounded off, said accumulators being adapted to accumulate hours and minutes as such, means for transferring the minutes part of the amount in the second accumulator to the first accumulator, means for causing subtraction of the amount in said device from the first accumulator, cycling means for causing in turn an operation of said first named transferring means and three successive operations of said subtracting means, means operative under control of said first accumulator and said cycling means during each of said three successive subtracting operations for ascertaining whether the amount in the first accumulator is a negative amount, means controlled thereby when the amount is a negative amount for rendering subsequent operation of said subtracting means ineffective, means for transferring the true value of the negative amount standing in the first accumulator to the second accumulator whereby there will be added thereto a number of minutes to raise the amount in the second accumulator to the next higher quarter hour, said cycling means causing an operation of said last named means after said successive operations have taken place.

4. In a machine for rounding off an amount expressed in hours and minutes to the next higher predetermined even subdivision of an hour, 30

5 a device settable to represent the minutes in said even subdivision, a first accumulator, a second accumulator settable to represent the amount to be rounded off, said accumulators being adapted to accumulate hours and minutes as such, means for transferring the minutes part of the amount in the second accumulator to the first accumulator, means for causing subtraction of the amount in said device from the first accumulator, cycling means for causing in turn an operation of said first named transferring means and a plurality of successive operations of said subtracting means, means operative under control of said first accumulator and said cycling means during each successive subtracting operation for ascertaining whether the amount in the first accumulator is a negative amount, means controlled thereby when the amount is a negative amount for rendering subsequent operation of said subtracting means ineffective, means for transferring the true value of the negative amount standing in the first accumulator to the second accumulator whereby there will be added thereto a number of minutes to raise the amount in the second accumulator to the next higher predetermined even subdivision of an hour, said cycling means causing an operation of said last named means after said successive operations have taken place.

FREDERIC VICTOR FREEBORN.
